US0D1069155S

(12) **United States Design Patent** (10) **Patent No.:** **US D1,069,155 S**
(45) **Date of Patent:** **** Apr. 1, 2025**

(54) **LABORATORY INSTRUMENT**

(71) Applicant: **Quantoom Biosciences, société anonyme**, Nivelles (BE)

(72) Inventors: **Anne De Lamotte**, Liège (BE); **Bastien Mairesse**, Uccle (BE); **José Castillo**, Brussels (BE)

(73) Assignee: **Quantoom Biosciences, société anonyme**, Nivelles (BE)

(**) Term: **15 Years**

(21) Appl. No.: **35/518,788**

(22) Filed: **Sep. 15, 2023**

(80) **Hague Agreement Data**

Int. Filing Date: **Sep. 15, 2023**

Int. Reg. No.: **DM/232330**

Int. Reg. Date: **Sep. 15, 2023**

Int. Reg. Pub. Date: **Oct. 27, 2023**

(57) **CLAIM**

The ornamental design for a laboratory instrument, as shown and described.

DESCRIPTION

1. Laboratory instrument

1.1 : Top, left, front perspective view

1.2 : Top, right, back perspective view

1.3 : Bottom, left, back perspective view

1.4 : Front elevation view

1.5 : Top plan view

1.6 : Bottom plan view

1.7 : Cross-sectional view taken through front to back center

1.8 : Bottom, right, front perspective view

1.9 : Front

1.10 : Left elevation view

1.11 : Right elevation view

The break lines in the reproductions 1.1 to 1.4 and 1.7 to 1.11 indicate that the appearance of any portion of the laboratory instrument between the break lines does not form part of the claimed design.

1 Claim, 11 Drawing Sheets
